Webster Electric Company, Racine, Wis., a cor-
poration of Delaware

Application December 17, 1953, Serial No. 28,117

Term of patent 14 years

(Cl. D26—14)

To all whom it may concern:

Be it known that I, James D. Floria, a citizen
of the United States, residing at Fox Point, Mil-
waukee County, Wisconsin, have invented a new,
original, and ornamental Design for a Combination
Magnetic Recorder and Reproducer, of which
the following is a specification, reference being
had to the accompanying drawing, forming a
part hereof.

Fig. 1 is a perspective view of a combination
magnetic recorder and reproducer embodying my
new design; and

Fig. 2 is a top plan view of the combination
magnetic recorder and reproducer shown in
Fig. 1.

The characteristic features of my new design
are shown in full lines in the drawing.

I claim:

The ornamental design for a combination mag-
netic recorder and reproducer, substantially as
shown and described.
